CLAIM

The ornamental design for a multifunctional travel pet water bottle with a detachable bowl as shown and described.

DESCRIPTION

FIG. 1 illustrates an isometric view of a multifunctional travel pet water bottle with a detachable bowl showing my new design.

FIG. 2 illustrates a front view of the multifunctional travel pet water bottle with the detachable bowl of FIG. 1.

FIG. 3 illustrates a rear view of the multifunctional travel pet water bottle with the detachable bowl of FIG. 1.

FIG. 4 illustrates a right side view of the multifunctional travel pet water bottle with the detachable bowl of FIG. 1.

FIG. 5 illustrates a left side view of the multifunctional travel pet water bottle with the detachable bowl of FIG. 1.

FIG. 6 illustrates a top view of the multifunctional travel pet water bottle with the detachable bowl of FIG. 1; and,

FIG. 7 illustrates a bottom view of the multifunctional travel pet water bottle with the detachable bowl of FIG. 1.
